UNITED STATES PATENT OFFICE.

ALBERT A. LARSON, OF ONAWA, IOWA.

FREIGHT-CAR DOOR.

Application filed March 31, 1922. Serial No. 548,506.

To all whom it may concern:

Be it known that I, ALBERT A. LARSON, a citizen of the United States, residing at Onawa, in the county of Monona and State 5 of Iowa, have invented new and useful Improvements in Freight-Car Doors, of which the following is a specification.

This invention relates to railway rolling stock, and particularly to door constructions 10 for freight cars, and has for its object the provision of a novel rolling door which is associated with a spring drum whereby the door normally tends to roll into a cylindrical form above the doorway, the door being capable of being pulled downwardly in 15 opposition to the action of the spring drum whereby to cover the opening.

An important object is the provision of a rolling door of this character which is 20 provided with novel means whereby it may be held in any desired position with the doorway entirely or partly uncovered as may be found advisable under various circumstances.

25 A further object is the provision of a door of this character which is so constructed that various strips constituting the door are arranged in such a way as to be weather tight and consequently exclude 30 wind, and the like from the interior of the car.

Another object is the provision of a device of this character which will be simple 35 and inexpensive in manufacture and installation, highly efficient in use, durable in service and a general improvement in the art.

With the above and other objects and 40 advantages in view, the invention consists in the details of construction to be herein- after more fully described and claimed, and illustrated in the accompanying drawings in which,

45 Figure 1 is a front elevation of my door associated with a freight car,

Figure 2 is a vertical sectional view taken through the door and showing it in closed position.

50 Figure 3 is a similar view and showing the door in open position.

Figure 4 is a horizontal sectional view taken on the line 4-4 of Figure 1.

55 Figure 5 is a detail sectional view showing the connection of the cables with the lower strip of the door,

Figure 6 is an enlarged elevation showing the latching device in the inoperative position,

Figure 7 is a detail section through the 60 spring roller,

Figure 8 is a detail section showing a slight modification of the strips, and

Figure 9 is a detail view of a modification showing a different means for connecting the door strips or sections.

Referring more particularly to the drawings the letter A designates a portion of the side of a freight car, B designates the door jambs located at opposite sides of the door opening, C represents the sill, and D 70 designates the lintel.

In carrying out my invention I provide a pair of brackets 10 which are secured upon the jambs B above the door opening and which are formed with rectangular openings within which are engaged the squared ends 11 of a shaft 12 which is surrounded by a coil spring 13 which has one end secured to the shaft and which has its other end secured to a cylindrical sleeve 14 which 75 is disposed in encircling relation to the spring and shaft. This constitutes a spring drum or roller structure and it will be apparent that the spring will operate to oppose rotation of the sleeve 14. The exact 80 location of the brackets and this spring roller structure is of no great consequence except that the location must naturally be above the door opening in the side of the car. Likewise there is not any restriction 90 as to whether the structure be mounted on the outside or the inside of the car though probably the latter is preferable.

The door proper comprises a plurality of horizontally disposed strips 15 which are 95 threaded upon a pair of flexible members such as wire cables or the like indicated at 16. These flexible members are secured to and trained about the sleeve 14 of the spring roller structure. The various strips 15 are 100 formed with holes 17 through which the flexible members pass and the lower most strip 18 is provided with holes 19 extending only partly therethrough for the reception of the lower ends of the flexible members, 105 the flexible members being secured to the lowermost strip by means of transverse pins or bolts 20 which pass therethrough and to which the flexible members are suitably connected. It will be observed that 110

the meeting edges of all the strips 15 are inclined as indicated at 21, the inclination being downwardly and outwardly with respect to the side of the car so as to exclude 5 water and wind from entering. If preferred, the edges of the strips may be rounded as shown at 21^a in Figure 8.

In Figure 9 I have shown the door strips as carrying leaves 21^b terminating at their 10 ends in knuckles 21^c which are pivotally connected and which take the place of the flexible members 17.

It should be stated that the confronting faces of the door jambs are formed with 15 suitable channel guides 22 within which the ends of the strips constituting the door are slidably engaged, these guides operating to prevent the strips from lateral displacement with respect to the door opening.

20 In order that the door formed by the plurality of strips carried by the flexible members might be held in any desired position within the door opening, I provide a latching device which comprises an elongated 25 horizontal rod 23 which has its end portions slidably mounted within suitable guides 24 secured upon the lowermost door strip 18 and which has its intermediate portion formed with an open loop 25 designed to be 30 swung downwardly over and into engagement with a triangular lug 26 carried by the strip 18, the engagement of the ends of the loop upon this lug operating to force the loop more widely open and consequently 35 move the portions of the rod 23 outwardly so that the extremities will frictionally engage the flanges of the guides 22. Located beneath the member 26 is a U bracket 27 which receives the loop 25 when the door is 40 closed. This U member is formed with holes through which may be passed the usual seal wire 28.

Assuming that the device has been 45 constructed and assembled as above described and as illustrated in the drawings, the operation is as follows: When the door is open it is apparent that all of the strips and the flexible members will be arranged in coiled formation upon the spring roller structure 50 at the top of the doorway so that there will be no obstruction to the door opening. When it is desired to close the door, it is necessary to pull all the strips downwardly by grasping the lowermost strip 18 until the 55 door has covered the entire door opening or as much thereof as is desired depending upon the circumstances, whereupon when the loop 25 is swung over the lug 26 the end portions of the rod 23 will be forced outwardly into 60 frictional engagement with the walls of the guides 22 so as to hold the door in this position with the spring 13 of the roller structure held under tension. When the door latching device formed by the rod 23 is 65 subsequently released it is apparent that the

tension of the spring 13 will operate to move the door into its open position. As above stated the meeting edges of the strips are inclined so as to exclude the weather and it is therefore apparent that the device should be very effective as a door and highly advantageous especially in view of the fact that when open it will occupy such a small space above the door opening.

70 While I have shown and described the door as intended for use in freight cars, it should be understood that it may be used wherever a rolling door is desired. It is also to be noted that I reserve the right to make such changes in the form, construction and arrangement of parts as will not depart from the spirit of the invention or the scope of the subjoined claims.

75 Having thus described my invention I claim;

1. In combination with the door jambs of a freight car provided on their confronting faces with guides, a door structure comprising a spring roller secured above the door opening, a rolling door carried by the spring roller and having its edges slidable along said guides, and a latching device for holding the door at a selected position consisting of an extensible rod mounted upon the door, and cam means mounted on the door engageable by the rod upon partial rotation thereof for forcing the end portions of said rod longitudinally in opposite directions to engage said guides.

80 2. In combination with the door jambs of a freight car provided at their confronting faces with guides, a door structure comprising a spring roller mounted above the door opening, a rolling door carried by said roller and having its edges slidable along said guides, a rod rotatably and somewhat slidably mounted upon the door having its intermediate portion formed as an open loop, and a cam projection on the door over which said loop may be forced to move the end portions of the rod longitudinally outwardly 85 into engagement with said guides.

90 3. In combination with the door jambs of a freight car provided at their confronting faces with guides, a door structure comprising a spring roller mounted above the door opening, a rolling door carried by said roller and having its edges slidable along said guides, a rod rotatably and somewhat slidably mounted upon the door having its intermediate portion formed as an open loop, and a cam projection on the door over which said loop may be forced to move the end portions of the rod longitudinally 95 outwardly into engagement with said guides, said loop being formed with inward projections, and said cam projection having a head with inclined sides upon which said inward projections ride when the loop is turned 100 downwardly.

4. In combination with the door jambs of a freight car provided with guides, a door structure comprising a spring roller mounted above the door opening, a rolling door carried by the spring roller and having its edges slideable along said guides, and a latching device for holding the door at a selected position consisting of a longitudinally extensible member rotatably mounted upon the

door and cam means mounted on the door 10 engageable by said member upon partial rotation thereof for moving the end portions thereof longitudinally outwardly to engage said guides.

In testimony whereof I affix my signature.

ALBERT A. LARSON.
